UNITED STATES PATENT OFFICE

2,191,014

TOBACCO PIPE

William D. Hensley, Majestic, Ky.

Application February 1, 1938, Serial No. 188,149

1 Claim. (Cl. 131—197)

The present invention relates to new and useful improvements in tobacco pipes, and has for its primary object to provide, in a manner as hereinafter set forth, a device of this character embodying a novel construction, combination and arrangement of parts through the medium of which the temperature of the smoke is reduced before reaching the mouth of the smoker.

Another important object of the invention is to prevent the entrance of tobacco juices into the mouth.

Other objects of the invention are to provide a tobacco pipe of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein—

Figure 1 is a longitudinal transverse sectional view of my invention.

Figure 2 is a fragmentary top plan view of the invention.

Figure 3 is a fragmentary view in transverse section taken substantially on the line 3—3 of Fig. 1.

Referring now to the drawing in detail, it will be seen that the reference numeral 5 designates the bowl of a pipe, which may be of wood or any other suitable material. The chamber 6 of the bowl 5 is enlarged as at 7 to provide a horizontal shoulder 8. Notches 9 are formed, in the side wall of the chamber 6 and extend downwardly from the shoulder 8 to form shoulders 10. The bowl 5 has extending therefrom the usual stem 11 through which the smoke duct 12 passes.

A cup shaped partition 13 constructed of metal or other suitable material has formed on its upper end portion lugs 14 which engage in the notches 9 for supporting the partition within the bowl 5 in spaced relation thereto.

A tobacco receiving bowl 15 constructed of clay, wood or other suitable material has formed at its upper end portion a flange 16 which seats in the enlarged portion 1 and rests on the shoulder 8, to support it in the cup-shaped partition 13 in spaced relation thereto. The bottom of the tobacco bowl 15 has openings 17 therein through which the smoke passes when the pipe is in use. The bottom face of the flange 16 is in a plane slightly above the plane of the upper end of the cup-shaped partition to provide a draft passage 18.

The smoke duct 12 in the stem 11 is enlarged as at 19 to receive one end portion 20 of the mouth piece 21. The mouth piece 21 has a smoke duct 22 extending therethrough which communicates, with the smoke duct 12 in the stem 11. 5 A recess 23 is formed in the end portion 20 of the mouth piece 21 to provide a trap for tobacco juices which may collect in the enlarged portion 19 of the duct 11.

When the pipe is in use, smoke is drawn 10 through the openings 17 into the space between the cup-shaped partition 13 and tobacco bowl 15. The smoke then passes through the passage 18, and down around the cup-shaped partition 13, through the space between the cup-shaped 15 partition 13 and the bowl 5, and into the smoker's mouth through the smoke ducts 11 and 22. As the smoke passes between the tobacco bowl 15 and cup-shaped partition 13 it is cooled with the result of condensation of tobacco juices therefrom, thus affording the smoker a cool dry smoke, as the tobacco juices are trapped in the bottom of the cup-shaped partition 13. When the smoker desires to drain the cup-shaped partition the tobacco bowl 15 is removed and the pipe is 25 inverted.

Although I have shown and described herein a preferred embodiment of my invention, it is to be definitely understood that I do not desire to limit the application of the invention thereto, 30 and any change or changes may be made in the materials and in the structure and arrangement of the parts within the spirit of the invention as claimed.

What is claimed is:

A tobacco pipe comprising an outer bowl, a stem connected with the bottom portion of the bowl, the upper end of the bowl having an internal annular groove therein, the bottom of which forms a shoulder and said bowl having 40 vertically arranged notches in the upper portion of its internal wall, the upper ends of which open out through said shoulder, an inner bowl having perforations in its bottom and an outwardly extending flange at its top, the outer 45 edge of said flange fitting in the groove and resting upon the shoulder, a cup-shaped partition located between the two bowls and having spaced outwardly extending lugs at its upper end which fit in the notches and having their upper ends 50 spaced from the lower face of the flange of the inner bowl to space the upper end of the partition from the under face of said flange to permit smoke to pass from the interior of the partition over the upper end thereof and then downwardly between the partition and the outer bowl. 55

WILLIAM D. HENSLEY.
